UNITED STATES PATENT OFFICE.

HARRY A. COLLEY, OF DETROIT, MICHIGAN, ASSIGNOR TO FROLASSET CORSET COMPANY, OF DETROIT, MICHIGAN, A CORPORATION OF MICHIGAN.

CORSET AND METHOD OF FORMING SAME.

1,414,114.

Specification of Letters Patent. Patented Apr. 25, 1922.

Application filed October 25, 1920. Serial No. 419,208.

To all whom it may concern:

Be it known that I, HARRY A. COLLEY, a citizen of the United States of America, residing at Detroit, in the county of Wayne 5 and State of Michigan, have invented certain new and useful Improvements in Corsets and Methods of Forming Same, of which the following is a specification, reference being had therein to the accompanying drawings.

10 This invention relates to a corset and it is the object of the invention to provide in a simple and novel manner, for flaring the portion of the corset adjacent the waist line of the garment and for varying the flare at 15 different circumferential points of the garment.

In the drawings:

Figure 1 is a view in elevation of a corset improved in accordance with the invention, 20 the same being shown opened out.

Figure 2 is a view showing the garment in use;

Figure 3 is a view illustrating a preliminary form of a strip of fabric which is required to variable flare when applied to the 25 corset.

Figure 4 is a vision similar to Figure 3 showing the fabric stitched together.

In these views the reference character A 30 designates a corset, the waist line of which is indicated at A'. The portion of the garment above the waist line is formed by a strip B, preferably elastic which is stitched to the main body of the garment along the 35 line A' and is required to flare to conform

to the curvature of the body above the waist line. This curvature varies at different circumferential points of the body and it is desirable to correspondingly vary the flare 40 of the strip B. To accomplish this result, said strip B, prior to attachment thereof to the body of the garment, has a plurality of V-shaped incisions extended from one edge thereof, as indicated at C C' C² in Figure 3, 45 the angle of said incisions being more or less acute according as the desired amount

of flare is large or small. The edges of these incisions are then stitched together as is shown in Figure 4 and the desired flare is imparted to the strip due to the resulting 50 difference between the lengths of the two edges of the strip. Finally the strip B is stitched to the edge of the garment along its shortened edge. Thus, in a very simple manner, the necessary flare is imparted to 55 the upper portion of the garment, and is diversified at circumferentially spaced points of the garment to properly conform to the body of the wearer. It will be understood that the described invention is not limited 60 in its application to a corset but may be applied to any garment requiring a diversified flare.

What I claim as my invention is—

1. A garment having a flaring marginal 65 portion formed separately from the main body of the garment and secured along one edge of said main body, said marginal portion being seamed transversely of said edge and said edge being variably shortened by 70 said seams.

2. The method of forming a garment with a flaring marginal portion consisting in extending a plurality of V-shaped incisions into said marginal portion from one edge 75 thereof, while said portion is separated from the body of the garment, securing together the edges of each V-shaped incision and attaching said portion to the body of the garment along the shortened edge thus produced. 80

3. The method of variably flaring a portion of a garment consisting in extending a plurality of V-shaped incisions into one edge of a strip of material, forming the angle of 85 said incisions more or less acute according as a large or small degree of flare is desired, stitching together the opposed edges of each incision and securing the shortened edge thus produced to the body of the garment. 90

In testimony whereof I affix my signature.

HARRY A. COLLEY.
